UNITED STATES PATENT OFFICE

ADAM J. MAY, OF ROCHESTER, NEW YORK, ASSIGNOR TO RITTER DENTAL MANUFACTURING COMPANY, INC., OF ROCHESTER, NEW YORK, A CORPORATION OF DELAWARE

HEADREST

Application filed December 29, 1928. Serial No. 229,294.

The present invention relates to a supporting structure, such for example, as a head rest adapted for use with dental, surgical and other types of chairs, and has for its object to provide improved apparatus of this class embodying a novel and advantageous arrangement of parts affording a simple construction and one which is convenient to operate and effective in service.

A further object of the invention is to provide in apparatus of the present type improved adjusting and locking means for the several connections and supporting members of the structure, in addition to improved means for temporarily holding said parts in predetermined positions of adjustment.

To these and other ends the invention resides in certain improvements and combinations of parts, all as will be hereinafter more fully described, the novel features being pointed out in the claims at the end of the specification.

In the drawings:

Fig. 1 is a rear elevation of a head rest structure, illustrating one embodiment of the invention;

Fig. 2 is a side elevation of the same;

Fig. 3 is an enlarged sectional elevation taken on line 3a—3a of Fig. 1, showing the clamping means for the several head rest sections adjusted to service position;

Fig. 4 is a similar view with the clamping means shown in release position;

Fig. 5 is a transverse section taken on line 5a—5a of Fig. 3;

Fig. 6 is a detailed perspective view of a link forming a part of the clamping means;

Fig. 7 is a fragmentary sectional elevation taken on line 7a—7a of Fig. 3;

Fig. 8 is a detailed fragmentary section taken on line 8a—8a of Fig. 2, and

Fig. 9 is an enlarged fragmentary section through a holding detent for one of the adjustable sections of the head rest structure.

Similar reference numerals throughout the several views indicate the same parts.

The present embodiment of the invention, while especially designed for use as an adjustable head rest structure, is not intended

to be limited to this particular usage, as it can be readily employed for adjustably supporting various articles, as will be understood upon consideration of the construction shown in the drawings. This arrangement embodies generally a bracket or standard 10, a supporting arm or member 11 and an interposed column or connection 12. The arm 11, in the present instance, forms a part of the head rest attachment and includes lateral branches 13, the spaced ends of which serve to pivotally support a yoke 15 carrying the pivoted head rest pads 16 and 17.

The bracket 10 is adapted for attachment to the back or other portion of a dental, surgical or other type of chair, not shown, and is preferably arranged to be slidably placed in guideways thereon. The bracket 10 carries an arm 18 extending upwardly and terminating in a horizontally disposed pivot member 19 upon which the column 12 is arranged to swing to different positions of adjustment. The lower end of the arm 11 terminates in a horizontally disposed pivot member 20 journaled in the upper end of the column 12. The opposite ends of the column are split to form upper and lower clamping jaws 21 and 22 respectively for holding the column and the arm 11 thereon in the desired positions of adjustment. The column has a bore or recessed portion 23 in which is disposed a clamping bolt 24. The lower end of the bolt is threaded to receive a nut 25 projecting within an opening formed in the clamping jaw 22 in alignment with the bore 23 of the column. The column has a recess 26 in which is disposed a spring 27, the lower end of which engages the nut 25 and the upper end an abutment 28 of the column, Fig. 4. The upper end of the clamping bolt is disposed within a recess 29 of the column and pivotally connected with the bolt at 30 is a link 31 extending upwardly through an opening in the clamping jaw 21. An operating lever 32 is provided for the link and is arranged to form therewith a toggle connection for exerting pressure upon the clamping jaws or members 21 and 22 to simultaneously urge them to clamping position upon the pivot.

members 20 and 19 respectively. The upper end of the lever is enlarged and provided with spaced side portions 33 forming a recess for the outer end of the link which is connected with the lever by a pivot pin 34, the ends of which are supported by the side portions, as indicated in Fig. 7. The upper end of the lever is disposed between upstanding lugs 35 on the clamping member 21 and a pin 36 forms a pivotal support for the lever, the opposite ends of the pin being supported by the lugs. The link is provided with an opening 37 through which the pin 36 extends, the opening being large enough to permit the link to swing between its extreme positions, indicated in Figs. 3 and 4. In Fig. 3, the lever is shown in the position to which it is moved to render the toggle effective by moving the pin 34 to the dead center point, at which it is held under the resistance of the spring 27 which serves to maintain the parts in operating position. In this position, the clamping jaws of the column 12 will be urged into engagement with the pivot members 19 and 20, whereby the arm 11 and column 12 will be firmly held in the desired positions of adjustment. When the lever 32 is swung to release position, the bolt 24 will move longitudinally in its bore, at which time the nut 25 will slide within the clamping jaw 22 from the position shown in Fig. 3 to that shown in Fig. 4, and the spring 27 will hold the parts in release position.

The nut, after having been properly adjusted to afford the necessary clamping action between the adjustable connections when moving the lever to the position shown in Fig. 3, is locked in position upon the bolt by a locking plate 38 removably secured by a screw 39 threaded into the end of the bolt 24. The plate is provided with a tongue 40 engaging a flattened portion 41 of the nut whereby the plate is prevented from turning upon the nut. The tongue 40 projects within a recessed portion 42 of the clamping jaw 22 and is prevented from turning therein through engagement with the side walls thereof. The nut may be adjusted upon the bolt whenever required after first removing the locking plate, which is subsequently replaced to hold the nut in adjusted position.

Means is provided for temporarily holding the arm 11 and the column 12 in normal position when the clamping means therefor is released. This means serves to prevent dropping of the parts from said normal position upon loosening the clamping means, thereby avoiding possible injury to the operator's hand or arms through striking of the same by said parts, should they swing under the influence of gravity from a high to a low position. The devices employed for this purpose are the same both for supporting the column 12 and the arm 11 so that a de-

scription of one will suffice for both. The holding means is best illustrated in Figs. 8 and 9. In Fig. 8, the pivot member 20 of the arm 11 carries a retaining plate 43 secured to the pivot member by a screw 44. Dowel pins 45 are carried by the pivot member and project into recesses formed in the retaining plate to insure turning of the latter upon rotation of the arm 11. The retaining plate adjacent its peripheral edge carries an outwardly projecting holder 46 in which is guided a detent in the form of a plunger 47 having an enlarged inner end portion 48 adapted to normally project into a recess 49 of the column 12 in which it is held by a spring 50 disposed within the holder 46. The spring pressed plunger prevents the arm 11 from dropping under the influence of gravity upon releasing the clamping means operated by the lever 32. Should it be desired to adjust the arm 11 to other than normal position from time to time whereby to adjust it under different conditions of usage, the operator can readily grip the arm and swing it about its axis to the desired position, at which time the rounded inner end 48 of the plunger will move out of the recess 49 and the outer end of the plunger will at the same time be projected through the outer end of the holder 46. The arm 11 will then be clamped in position by swinging the lever 32 to the position shown in Fig. 3. In this or any other but normal position the end of the plunger projecting from the holder 46 will serve as an indicator to remind the operator to first grip the arm before releasing the clamping means in order to prevent its dropping to a lower position, thereby preventing any possible injury either to the operator, or to the patient within the chair or any injury to the parts by the striking of one against the other. Furthermore, when the plunger does not project beyond the holder 46, this fact will be an indication to the operator that the head rest is in normal position.

The same is true with regard to the holder 12 upon the pivot member 19 of the bracket arm 18. In this case, however, the pivot member 19 and retaining plate 43 are fixed and the column 12 is rotated relative thereto, but the principle is the same and the plunger 47 will function to indicate to the operator whether or not the column is in normal position. By the term "normal position" is meant the position at which it is preferred to maintain the head rest pads under normal conditions of usage. It will be understood, however, that the parts may be adjusted and firmly clamped in position through the action of the toggle mechanism in any desired position other than the normal position shown.

It will also be understood that when the toggle is moved to release position for the purpose of adjusting the arm 11 upon the

column 12, the latter will be prevented from shifting its position, since it will be held by the detent or plunger engaging within the recess provided therefor in the lower end of the column.

5 I claim as my invention:

1. In a head rest supporting structure, the combination of a pair of supporting members, one of which is arranged to swing relative to the other and having a part for holding it in fixed relation thereon and means on one of said members for operating said holding part comprising a toggle arrangement including relatively movable parts and a hand controlled element for effecting operation and release of the holding part, said element being pivoted at one point upon said last mentioned member and pivotally receiving at a different point one of said relatively movable parts.

2. In a head rest supporting structure, the combination of a pair of supporting members, one of which is arranged to swing relative to the other and having a part for clamping it in fixed relation thereon and toggle means on one of said members comprising a lever pivoted thereon and interengaging connections extending longitudinally of the last mentioned member between the lever and 30 clamping part for actuating the latter, one of said connections pivotally engaging said lever at a point spaced from that at which it is pivotally connected with said last mentioned member.

3. In a head rest supporting structure, the combination of a pair of supporting members, one of which is movable relative to the other and having a part for holding it in fixed relation thereon and actuating means for 40 said part comprising elements extending longitudinally of one of said supporting members, said elements being connected at their inner ends, one of said elements having its outer end operatively connected with said holding part and a lever pivoted upon said last mentioned supporting member at one point and also pivotally connected with the other of said elements at its outer end whereby to exert a pull upon said elements to effect 50 operation of the holding part.

4. In a head rest supporting structure, the combination of a pair of supporting members, one of which is arranged to move relative to the other and having a part for holding it in fixed relation thereon, means on one of said members for operating said holding part comprising a toggle arrangement including a hand controlled member for effecting operation and release of the holding part and yieldably mounted means acting to resist movement of said supporting members one relative to another and serving to indicate when said members are in different positions of adjustment.

5. In a head rest supporting structure, the

combination of a pair of supporting members, one of which is arranged to swing relative to the other and having a part for holding it in fixed relation thereon, means on one of said members for operating said holding part comprising a toggle arrangement including a hand controlled lever for effecting operation and release of the holding part, one of said supporting members having a recess therein and a spring pressed plunger carried by the other of said members arranged to take into said recess to hold said members in a predetermined relationship.

6. In a head rest supporting structure, the combination of a pair of supporting members, one of which is arranged to swing relative to the other and having a part for holding it upon the latter in different positions of adjustment, means on one of said members for operating said holding part comprising a toggle arrangement including a hand controlled member for effecting operation and release of the holding part, one of said supporting members having a recess therein, a guide secured upon the other of said members for movement therewith, a spring pressed plunger slidably mounted upon the guide arranged to take into said recess whereby to maintain said members in a predetermined relationship when said holding part is moved to release position, said plunger serving as means to indicate when the supporting members are in said predetermined relationship.

7. In a head rest supporting structure, the combination of a pair of supporting members, a tubular connection between the same adjustable relative to said members, said connection having at its opposite ends clamping parts movable one toward another and operating to secure it in different positions of adjustment with respect to said supporting members, and toggle means comprising relatively movable parts disposed within said tubular connection one of which is connected with one of the clamping parts and the other extending from the connection and an operating element pivotally engaging another of said parts and mounted to swing upon said connection.

8. In a head rest supporting structure, the combination of a pair of supporting members, a connection between the same adjustable relative to each of said members, said connection having end clamping parts at its opposite extremities by which to secure it in different positions of adjustment with respect to said supporting members, a lever pivoted directly upon one of said end clamping parts, and means arranged to be operated by the lever to move said parts simultaneously to clamping position, said means including an element pivotally connected with the lever.

9. In a head rest supporting structure, the combination of a pair of supporting members

having pivot bearings thereon, a connection between the same arranged to swing upon said bearings relative to said members, said connection having at its opposite ends clamping jaws engaging said bearings and movable one toward another, a lever pivoted upon one of said clamping jaws, and means connected with the other clamping jaw and pivoted upon the lever to move said jaws one toward another when the lever is moved to clamping position.

10. In a head rest supporting structure, the combination of a pair of supporting members, a tubular connection between said members adjustable upon one and on which the other member is mounted for adjustment, clamping parts for holding said connection and one of said members in different positions of adjustment, toggle means including a lever for operating said clamping parts and yieldable means acting to resist movement of the toggle means to service position and operating to release the clamping parts when the lever is moved to a predetermined release position.

25. 11. In a head rest supporting structure, the combination of a pair of supporting members, a connection between said members adjustable upon one and on which the other member is mounted for adjustment, clamping parts for holding said connection and one of said members in different positions of adjustment, relatively movable interengaging elements disposed within said connection for longitudinal movement thereof, one of which 30 is connected with one of said clamping parts and an operating member pivotally connected with the other of said clamping parts and having a separate pivotal connection with one of said interengaging elements.

40. 12. In a head rest supporting structure, the combination of a pair of supporting members, a connection between said members adjustable upon one and on which the other is mounted for adjustment, clamping parts on 45 said connection arranged to cooperate with said supporting members to hold the connection and one of said supporting members in different positions of adjustment and toggle means for operating said 50 clamping parts comprising relatively movable parts extending longitudinally within said connection and an additional part pivoted upon said connection and having a separate pivotal connection with one of said relatively 55 movable parts.

13. In a head rest supporting structure, the combination of a pair of supporting members, a connection between said members adjustable upon one and on which the other is mounted 60 for adjustment, clamping parts on said connection arranged to cooperate with said supporting members to hold the connection and one of said supporting members in different positions of adjustment and toggle means for 65 operating said clamping parts including a

pair of pivotally connected elements extending longitudinally of the connection between said clamping parts and an operating member for said elements comprising a hand lever pivoted at one point upon said connection and pivotally connected at another point with one of said elements.

14. In a head rest supporting structure, the combination of a supporting bracket, a supporting member spaced therefrom, a connection between said bracket and said member adjustable upon the bracket and on which said member is mounted for adjustment, said connection including end portions forming 80 clamping parts for holding it in adjusted position upon said member and said bracket, a lever pivoted upon one of the end portions and means interposed between the lever and the other end portion including an element having pivotal connection with the lever and arranged to be moved by the lever whereby said clamping parts are moved to clamping position.

15. In a head rest supporting structure, the combination of a pair of supporting members, a connection between the same having a main body portion and clamping parts movable thereon, one for clamping the connection upon one of the said supporting members and the other for clamping the other supporting members upon the connection, a lever pivoted upon one of the movable clamping parts and means operatively connected with the other clamping part including an element having pivotal connection with and arranged to be actuated by the lever, said means and said lever cooperating upon operation of the latter to move said clamping parts to clamping position.

16. In a head rest supporting structure, the combination of relatively adjustable supporting members connected one with another, one of said members having a securing part by which it is held in different positions of adjustment upon the other, operating means for said securing part comprising a hand grip element pivoted upon one of said supporting members, and relatively movable cooperating devices interposed between said securing part and said hand grip element one of said devices having pivotal connection with the hand grip element at a point spaced from that at which said element is pivotally connected with its supporting member.

17. In a head rest supporting structure, the combination of relatively adjustable supporting members connected one with another, one of said members having a securing part by which it is held in different positions of adjustment upon the other, operating means for said securing part comprising a hand grip element pivoted upon one of said supporting members, a link extending longitudinally of the last mentioned supporting member and pivotally connected with said

hand grip element, and a connection between the link and said securing part for holding the latter in securing position when the hand grip element is in a predetermined position 5 of adjustment.

18. In a head rest supporting structure, the combination of relatively adjustable supporting members connected one with another, one of said members comprising a 10 tubular column having a securing part at one end by which it is held in different positions of adjustment upon the other member, and toggle means for moving and holding said part in securing position comprising 15 connected elements placed end to end within the tubular column, one of said elements projecting from the end of the column opposite that having the securing part thereon, and a hand grip lever pivoted upon said column 20 and having pivotal connection with the end of the element projecting from the column.

19. In a head rest supporting structure, the combination of spaced supporting members, a tubular column interposed between 25 said members, said members having bearing portions journaled in the opposite ends of the column permitting relative adjustment between the column and the supporting members, said column having relatively 30 movable end clamping jaws engaging the bearing portions of said supporting members, a rod extending longitudinally within the column and connected at one end with one of said jaws, a link connected with the 35 other end of the rod and projecting through the other of said jaws, and a lever pivoted at one point upon the last mentioned jaw and pivotally connected at another point with the projecting portion of said link.
